[57] **CLAIM**

The ornamental design for a basketball novelty clock, as shown and described.

DESCRIPTION

FIG. 1 is a front elevational view of a basketball novelty clock showing my new design;

FIG. 2 is a left side view thereof, the opposite side being a mirror image;

FIG. 3 is a top plan view thereof;

FIG. 4 is a bottom plan view thereof; and,

FIG. 5 is a rear elevational view thereof.

It is understood that the dot-dash of FIGS. 3 and 4 indicate that the net portions are continuous.
